UNITED STATES PATENT OFFICE.

FRANK W. HOWARD, OF NEW YORK, N. Y.

RAINCOAT.

1,374,301.

Specification of Letters Patent. Patented Apr. 12, 1921.

Application filed October 16, 1919. Serial No. 330,970.

To all whom it may concern:

Be it known that I, FRANK W. HOWARD, a citizen of the United States, residing in the city of New York and State of New York, have invented new and useful Improvements in Raincoats, of which the following is a specification.

This invention relates to raincoats or waterproof cloaks of the general type disclosed in my Patent #1,229,270, dated June 12, 1917.

This waterproof cloak is of very simple construction, particularly adapting it to be produced from waterproof paper, with the idea that these raincoats can be produced at a very low cost and kept in stock at different places so that they will be available at a low price for persons who have been accidentally caught in the rain.

The raincoat includes a cape portion and a body portion. The general object of the present invention is to provide an efficient raincoat of such a construction as will prevent substantially any waste in cutting the cape and body of the raincoat from the material out of which the garment is formed. A further object is to produce a blank of very simple form, from which the cape and body portion of the raincoat can be readily produced, and also to provide for reinforcing the point of connection between the cape and the body of the raincoat; also to provide a blank of improved form which will insure an ample overlap of the skirt portion of the garment; and to provide simple means for shaping the skirt portion to the body and for mounting a belt-cord near the waist line of the garment. One of my objects has been to provide a raincoat having a large overlap of the front flaps.

Further objects of the invention will appear hereinafter.

The invention consists in the novel features, and in the general combination of parts to be particularly described hereinafter, all of which contribute to produce a simple and efficient raincoat, and blank for forming the same. A preferred embodiment of my invention will be particularly described in the following specification, while the broad scope of my invention will be pointed out in the appended claims.

In the drawing,

Figure 1 is a plan showing the preferred form of blank from which my improved raincoat can be formed;

Fig. 2 is a front elevation of the complete raincoat;

Fig. 3 is a horizontal section taken through the skirt-portion of the raincoat on the line 60 3—3 of Fig. 2;

Fig. 4 is a diagrammatic view indicating how the blank may be arranged on the material to prevent waste;

Fig. 5 is a vertical section taken on the 65 breast of the garment and illustrating upon a large scale, the manner of securing the extensions of the front flaps of the skirt-portion to the flaps of the cape-portion; and

Fig. 6 is a vertical section taken about on 70 the line 6—6 of Fig. 2, to illustrate details of the construction at the neck of the garment.

In cutting out the raincoat, I form the blank or pattern in such a way that a back 75 is formed to connect to the collar of the cape, and by cutting the upper portion of this back from the cape-portion of the blank, I form the neck opening. Also the ends of the cape are cut so as to produce reentrant angles in the body-portion of the blank, and these angles come under the arms when the garment is worn. In this way, I avoid any waste.

In accomplishing this, I prefer to utilize 85 a blank having the general characteristics illustrated in Fig. 1, that is to say, it includes a body-portion 1 of general quadrilateral form having a central longitudinal axis 2, and having side edges 3 which diverge in the direction of the lower edge 4 of the bracket. The upper part of the blank consists of a cape-portion 5 of substantially oval shape, the longitudinal axis of the oval being disposed substantially at right angles 90 to the central axis 2 of the entire blank. The ends of the cape-portion 5 are preferably formed by curved lines 6, and the blank is provided with indicated cutting lines 7 which constitute continuations of the lines 100 6, and extend down into the body portion 1 to two opposite points 8, that is to say, these lines converge toward each other in a downward direction until they arrive at the points 8. Beyond these points, indicated cutting 105 lines 9 are provided which are preferably substantially straight, and these lines may converge toward each other in an upward direction so that they form a tapering part extending toward the cape-portion 5. The material between these lines is to form the upper portion of the back.

I prefer to form the upper part of the body-portion into a relatively narrow tongue 10 which extends up into the cape-portion, the side edges of the tongue 10 being indicated by cutting lines 11 which are substantially parallel with the central axis 2. It should be understood that at the location of the transverse dotted lines 12, at the end of the tongue 10, the back of the neck 10 opening of the collar of the cape is formed, the side edges of the neck opening being formed at the points indicated by the lines 11.

By reason of the fact that the lines 7 and 15 9 produce reentrant angles, the vertices of which are at the points 8, it will be evident that the blank will present oppositely disposed upward extensions or necks 13 which constitute the upper portions of the oppositely disposed side flaps 14 which will form the front of the skirt-portion of the garment.

According to my invention, I may form the cape-portion 5 into the cape without disconnecting it from the skirt-portion of the blank, and this is the procedure, if the material such as waterproof paper has been waterproofed on both faces. If such is the case, instead of cutting the cape-portion 30 from the skirt-portion at the lines 12, I simply produce a plurality of transverse folds at this point, the width of which is indicated by the distance between the transverse dotted lines 12. These folds may be 35 packed together so as to form a reinforcement 15 at the back of the neck opening, (see Fig. 6), the said folds being secured together by fasteners of any kind, for example, by a plurality of eyelets 16.

40 In the finished garment, the points 8 of the reentrant angles are adapted to come under the arms, of the person wearing the coat, and in order to shape this armless skirt-portion to the figure of the body, I 45 provide the blank with a plurality of indicated plaiting lines 17 which extend from these angles in a downward direction and converge toward each other. These lines operate as folding lines for the garment and 50 also tend to reduce the measure of the garment at or near the waist-line, as will be referred to again hereinafter.

I also provide similar plaiting lines 18 near the ends of the cape-portion, which 55 diverge from a common point, and these plaiting lines are adapted to come over the shoulder and cause the cape to droop and hang nicely from one's shoulders.

With this form of blank, it will be evident 60 that the cape-portion is formed into two flaps 5^a and 5^b located, respectively, on opposite sides of the central axis 2.

In forming a raincoat such as illustrated 65 in Fig. 2 from a blank such as described above, the cape-portion 5 should be folded

backwardly on the line 12 and the collar reinforcement 15 is formed in the manner described. The flaps 14 of the body-portion are then folded inwardly so that the edges 3 cross each other at an elevated point and diverge from each other in a downward direction. In this way, on account of the inclined direction of the edges 3, a relatively large overlap is formed at the front lower portion of the raincoat. The upward extensions 13 of the flaps 14 are then attached to the underside of the cape flaps 5^a and 5^b by means of suitable fastening devices such as eyelets 19 and tie-buttons 20. I prefer to reinforce this attaching point by providing a reinforcement. This is produced by folding the material again and again upon itself, thereby producing a plurality of folds 21 in the upper ends of the extension 13, (see Fig. 5). Through this reinforcement, the eyelets 19 and the eyelets 22 of the tie-buttons pass.

I also prefer to attach together the folds 23 of the side plaits 24 of the skirt-portion, by means of eyelets 25, which align with each other. I also prefer to provide a belt in the form of a cord 26 which passes around the skirt-portion of the garment near the waist line. Any suitable means may be provided for supporting this belt; this is preferably accomplished simply by passing the cord through the eyelets 25, the ends of the cord being tied together at the front of the garment with a suitable bow 27, after the garment is put on.

Any suitable means may be provided for securing the overlapping cape flaps together at the front of the garment, and this means preferably consists of a simple cord 28 for connecting the buttons 20.

Any suitable means may also be provided for securing the lower portion of the skirt flaps to each other, for example, for this purpose I may provide a cord 29 and button 30. If desired, reinforcement may be placed under the buttons 30, and also if desired, the edges of the neck opening 31 may be strengthened by a suitable reinforcing strip 32 running continuously along the inner edge or collar of the cape.

It is understood that the embodiment of the invention described herein is only one of the many embodiments my invention may take, and I do not wish to be limited in the practice of my invention nor in my claims, 120 to the particular embodiment set forth.

What I claim and desire to secure by Letters Patent is:

1. A rain-coat having an armless skirt-portion with a back extending upwardly at the rear, said skirt-portion having a pair of forwardly disposed flaps overlapping each other at the front lower portion, and having inclined forward edges diverging from each other from an elevated point at the front of 130

- the garment whereby an increased width of overlap of said flaps is produced at the lower edge of the skirt-portion, a cape having two front flaps and a collar connecting with said back at the upper end thereof whereby the rear portion of the cape is suspended from said collar, said skirt-portion having forward extensions extending upwardly under said cape and attached respectively to the front flaps of said cape, said skirt-portion having plaits at the sides thereof, and a cord passing around the outer side of the skirt at said plaits.
2. A rain-coat having an armless skirt-portion with a back extending upwardly at the rear, said skirt-portion having a pair of forwardly disposed flaps overlapping each other at the front lower portion and having inclined forward edges diverging from each other from an elevated point at the front of the garment whereby an increased width of overlap of said flaps is produced at the lower edge of the skirt-portion, a cape having two front flaps, and a collar connecting with said back at the upper end thereof, said skirt-portion having forward extensions extending upwardly under said cape and attached respectively to the front flaps of the cape, said skirt-portion having plaits at the side thereof and eyelets connecting the folds of said plaits, and a belt cord passing through said eyelets and around the outer side of the skirt.
3. A rain-coat adapted to be formed of water-proof paper having an armless skirt-portion with a back tapering in width and terminating in an upwardly extending tongue, said skirt portion having a pair of forwardly disposed flaps overlapping at the front, a cape having two front flaps, and having a collar, said tongue having a plurality of folds formed therein and connected to said collar at the back edge of the neck opening, the front flaps of said cape having means for attaching the same together, said skirt-portion having forward extensions extending up under the front flaps of the cape and attached respectively thereto, said cape having side plaits adjacent the shoulders increasing in width toward the outer edge of the cape, said skirt-portion having side plaits with eyelets therein and a cord belt passing through said eyelets and passing around the outer side of the skirt-portion.
4. A blank for a garment having a cape, 55 consisting of a body portion of quadrilateral form having a central longitudinal axis, a cape portion of substantially oval form disposed symmetrically with respect to said central axis and having its longitudinal axis 60 disposed substantially at right angles to the said central axis, the ends of said cape portion being cut from the body portion of the blank whereby reentrant angles are formed in the body portion of the blank, to come 65 under the armholes of the garment, said blank having a centrally disposed tongue extending into the cape portion to form the upper part of the back of the garment.
5. A blank for a garment having a cape, 70 having a general quadrilateral shape with a central longitudinal axis, the upper edge of said blank being in substantially the form of an oval with its longitudinal axis transverse to said first axis, to form the cape, said 75 blank having indicated cutting lines extending from the ends of the oval into the interior of the quadrilateral to oppositely disposed points, said blank further having indicated cutting lines extending from said 80 points and converging toward the said central axis and toward the longitudinal axis of the oval, and cutting lines connecting with said last named cutting lines and extending up into the oval substantially parallel with the first named central axis.
6. A blank for a rain-coat having a cape consisting of a body portion in the form of a quadrilateral, having a central axis and side edges diverging toward the lower edge 90 of the quadrilateral, a substantially oval cape portion having its longitudinal axis disposed substantially at right angles to said central axis, said cape portion comprising 95 two oppositely disposed flaps formed by cutting reentrant angles into the upper portion of the body portion of the blank, said reentrant angles located so as to come under the armholes of the rain-coat, said body portion having an upwardly extending central tongue projecting into the middle part of the cape portion and cut therefrom so as to 100 form edges for the neck opening in the finished cape.

In testimony whereof, I have hereunto set 105 my hand.

FRANK W. HOWARD.
